Primary Examiner — Wendy L Arminio(74) *Attorney, Agent, or Firm* — Olson & Cepuritis, Ltd.(57) **CLAIM**

The ornamental design for a safety cap for a bottle, as shown and described.

DESCRIPTION

FIG. 1 is a top perspective view of a safety cap for a bottle shown in a closed position and in a position of use on an unclaimed bottle drawn in broken lines;

FIG. 2 is a side perspective view of the safety cap for a bottle of FIG. 1 shown in a position of use on an unclaimed bottle drawn in broken lines;

FIG. 3 is a top plan view of the safety cap for a bottle of FIG. 1 but shown removed from the bottle;

FIG. 4 is a bottom plan view thereof;

FIG. 5 is a front end view thereof;

FIG. 6 is a back end view thereof;

FIG. 7 is a side end view thereof;

FIG. 8 is an opposite side end view thereof; and,

FIG. 9 is a top perspective view of the safety cap for a bottle of FIG. 1 shown with a sliding closure portion in an open position.

The broken lines illustrating a bottle in FIG. 1 and FIG. 2 depict environment and form no part of the claimed design. All other broken lines depict portions of the safety cap for a bottle that form no part of the claimed design.

1 Claim, 6 Drawing Sheets(56)
